UMBRELLA

Heinz Weber, Hilden, Germany, assignor to
Bremshay AG, Solingen, Germany

Filed Jan. 27, 1972, Ser. No. 221,493

Term of patent 14 years

Int. Cl. D3—03

U.S. Cl. D88—3 A

FIG. 1

FIG. 2

FIG. 3

FIG. 4

FIG. 1 is a top perspective view of an umbrella showing my new design, the frame structure, not shown, being conventional;

FIG. 2 is an enlarged fragmentary top plan view of the center portion thereof;

FIG. 3 is an enlarged fragmentary side elevational view thereof; and

FIG. 4 is an enlarged fragmentary end elevational view thereof.

The characteristic feature of my new design resides in the crown-cap as best shown by FIGS. 2—4.

I claim:

The ornamental design for an umbrella, as shown and described.
